METHOD OF MANUFACTURING OIL GAS

Filed Nov. 12, 1925

Patented Jan. 8, 1929.

1,698,526

UNITED STATES PATENT OFFICE.

ALVIN J. BASSETT, OF MILWAUKEE, WISCONSIN, ASSIGNOR TO THE BRUCE MACBETH ENGINE COMPANY, OF CLEVELAND, OHIO, A CORPORATION OF OHIO.

METHOD OF MANUFACTURING OIL GAS.

Application filed November 12, 1925. Serial No. 68,544.

My invention relates to methods of controlling the volume of oil gas produced in a process of gas manufacture, wherein air and oil, are mixed, introduced into a chamber, there converted into combustible gas and then withdrawn from said chamber through a discharge duct connected with an internal combustion engine, furnace or other device in which it is to be consumed. Certain means are shown in the accompanying drawing and hereafter described to illustrate mechanism by which my improved method may be carried out, such mechanism forming the subject matter of my pending application upon oil gas apparatus, filed November 12, 1925, Serial No. 68542.

The object of the invention is to vary the volume of oil gas manufactured in accordance with the demand therefor made by the consuming device and effect such variation in a simple and expeditious manner.

This object I accomplish in the particular manner hereinafter described, by providing unloading means for the air supplied for making the gas and for producing the pressure upon the oil, and varying the amount of air unloaded by means of a regulator controlled by the pressure in said duct whereby the amount of air and oil supplied will vary at a rate inversely proportional to such pressure.

The said invention consists of a method hereinafter fully described and particularly set forth in the claims.

The annexed drawing and the following description set forth in detail certain means for carrying out my invention, the disclosed means, however, constituting but one of the various mechanical forms in which the steps of my invention may be employed.

In said annexed drawing:

Figure 1 represents a side elevation, partly in vertical axial section of a gas-making apparatus by means of which my improved method may be carried out.

Fig. 2 represents, upon an enlarged scale, an axial section of the regulator forming part of the apparatus.

In the illustrated device a converter 1 of the type shown and described in my pending application Serial No. 717,071, filed May 31st, 1924, is provided and supplied from the mixing tube 2 with a mixture of oil and air. The oil is supplied from a pipe 3 connected with

the pressure from branch pipe 5 connected with the main air pipe 6 which is supplied from the outlet of the air pump 7, which supplies a constant pressure.

This oil is discharged into the mixing tube 80 simultaneously with air from the air pipe 8. This latter pipe is connected with a chamber 9 which is heated by the produced gas emanating from the converter which chamber receives its air supply from the main air pipe 6. 65

The produced gas passes from the converter through a main outlet pipe 10 into a scrubber 11, through a pipe 12 into a tar extractor 13 and thence into the main gas delivery pipe 14 which leads to a furnace 26, 70 a gas engine or other gas utilizing apparatus which is to be supplied with such gas.

The construction thus far described is similar to that of my above-mentioned application. 75

As is well known, the demand upon the supply of the produced gas varies. In the case of an internal combustion engine, it varies with the load upon the engine, and in the case of a furnace it varies as the furnace 80 valves are opened or closed to supply more or less gas thereto during its operation.

In order to increase or decrease the supply in accordance with the demand, I provide the above-described apparatus with the following accessories. 85

The main air-pipe 6 is connected near the pump 7 by means of a pipe 15 with the side of the valve chamber in the casing of a valve 16, the bottom of such chamber being connected with a pipe 17 whose lower end is connected with the air inlet pipe 18 of the pump 7, said inlet pipe communicating with the atmosphere. The movable member 19 of the valve, Fig. 2, controls communication between the pipes 15 and 17, and it will be seen that when valve 16 is open, air will be unloaded or diverted from pipe 6 through pipes 15 and 17 and go back to the pump, said two pipes together forming an unloading duct. 90 This results in the discharge finally into chamber 9 from pipe 6, and hence into the converter from the mixing pipe 2, of a given amount of air, such amount depending upon the size of opening in the valve 16 and hence 95 the amount of air which is unloaded. When said valve 16 is closed, a maximum, and when wide open a minimum of air will be supplied to said converter.

The pump 7 is a constant displacement 110

- pump, and if the valve 16 is completely closed so that the suction in pipe 17 is zero, then the air pressure of the pump is at a maximum or, otherwise stated, it is working at its predetermined pressure. However, as the valve 16 is more or less opened, according to the building up of the pressure in delivery pipe 14, then the pressure of the pump 7 is scaled down from maximum to zero as a minimum, whereby the load on the pump and the cost of operating same is accordingly reduced. Thus the working air pressure, or the air pressure effectively used, is throttled all the time inversely proportional to the demands on the gas-making apparatus. In other words, the load on the pump 7 is in proportion to the oil-gas delivery from the pipe 14. Instant control of the gas-making operation is thus afforded.
- 20 Connected with the movable valve member 19 is a diaphragm 20 of a regulator 21 whose interior pressure chamber 21' is divided into two compartments by said diaphragm. One of these compartments communicates with 25 one end of a regulator pipe 22 whose other end is connected with the main gas pipe 14 so that when the pressure in said gas pipe falls, the diaphragm moves to actuate the valve member 19 to close or decrease the valve opening, and vice versa.
- In operation, therefore, when demand for gas increases, the pressure in oil-gas delivery pipe 14 decreases, the opening in the valve 16 is diminished and the amount of air delivered to the converter increases, the air pressure in pipe 6 increasing coincidentally. 35 Such increase of air pressure is communicated to the oil in tank 4 and a corresponding increase of the oil supply and a corresponding increase in the production of gas is effected.
- 40 When the demand for gas diminishes the opening in valve 16 is increased, the amount of air and oil diminished and the amount of gas produced is decreased, as will now be apparent.

It will therefore be observed that the amount of gas produced varies at a rate inversely proportional to the pressure in the main gas outlet pipe 14.

What I claim is:

1. The method of manufacturing oil gas and regulation of the production thereof which consists, in maintaining an oil supply, maintaining an air supply in communication with means adapted to develop a pressure different from atmospheric pressure, conveying the air so acted upon and oil to a mixer, introducing the mixture into a converter, converting the mixture into oil gas, and withdrawing the oil gas from the converter through a discharge duct, the latter being subject to demands for oil gas, air being continuously unloaded from the air-conveying means intermediate the pressure developing means and the mixer in amounts inversely proportionate to the demands, and the oil being conveyed to the mixer by the actual working air pressure which remains after said unloading operation. 60

2. The method of manufacturing oil gas and regulation of the production thereof which consists, in maintaining an oil supply, maintaining an air supply in communication with means adapted to develop a pressure different from atmospheric pressure, conveying the air so acted upon and oil to a mixer, introducing the mixture into a converter, converting the mixture into oil gas, and withdrawing the oil gas from the converter through a discharge duct, the latter being subject to demands for oil gas, air being continuously diverted, in amounts inversely proportionate to the demands, from the air-conveying means back to the pressure-developing means, and the oil being conveyed to the mixer by the actual working air pressure which remains after said diverting operation. 80

Signed by me this 31st day of October, 1925.

ALVIN J. BASSETT.
